Primary Examiner — Mary Shannon Malley(74) *Attorney, Agent, or Firm* — Davidson Law Group, ALC; Payam Moradian(57) **CLAIM**

I claim the ornamental design for UV sanitizer, as shown and described.

DESCRIPTION

FIG. 1 is a back view of the UV sanitizer;

FIG. 2 is a left view thereof;

FIG. 3 is a right view thereof;

FIG. 4 is a front view thereof;

FIG. 5 is a back isometric view thereof;

FIG. 6 is a front isometric view thereof;

FIG. 7 is a top plan view thereof; and,

FIG. 8 is a bottom plan view thereof.

The Broken lines are for the purpose of illustrating the UV sanitizer and form no part of the claimed design.

1 Claim, 6 Drawing Sheets(56)
